UNITED STATES PATENT OFFICE.

CARLTON T. MATTHEWS, OF GREEN BAY, WISCONSIN, ASSIGNOR OF ONE-HALF TO HAROLD K. MATTHEWS, OF GREEN BAY, WISCONSIN.

TIE PLATE.

Application filed May 29, 1926. Serial No. 112,589.

This invention relates to tie plates and one object of the invention is to provide a tie plate which may be securely held upon a tie by rail spikes and prevent a rail from having transverse or longitudinal creeping movement, as well as serving to protect the tie from damage by pounding as a train moves along the track.

Another object of the invention is to so form the tie plate that an anchor bar, secured to the base of a rail, may have interlocking engagement with the plate and very effectively prevent longitudinal creeping of the rail.

10 Another object is to provide a rail anchor which may be releasably but firmly secured to a rail and move vertically with the rail independent of the tie plate as a train passes over the rail.

15 Another object is to provide a rail anchor which may be releasably but firmly secured to a rail and move vertically with the rail independent of the tie plate as a train passes over the rail.

20 This invention is illustrated in the accompanying drawings, wherein,—

Figure 1 is a top plan view showing the improved tie plate and rail anchor applied to a fragment of a rail.

25 Figure 2 is a view showing the rail in transverse section along the line 2—2 of Figure 1 and tie plate in end elevation.

Figure 3 is a perspective view of the tie plate, and

30 Figure 4 is a side elevation, looking at the inner side face of the anchor securing wedge.

The tie plate and rail anchor forming the subject matter of this invention are intended for use in railroad construction and are to be applied to a tie 1 and form a chair for the rail 2. The plate is indicated in general by the numeral 3 and may be formed of steel or any other strong metal which will successfully resist pounding, to which it is subjected as a train moves along a track. The tie plate extends transversely beneath the base of the rail, as shown in Figure 2, and is formed with openings 4 through which spikes 5 may be passed to hold the plate upon the tie and retain the rail seated upon the plate. Ribs 6 extend upwardly from the plate with their inner faces alined with the inner edges of the spike receiving openings and serve to engage the side edges of the rail base and prevent the rail from having movement transversely of the track. The rails of a track will, therefore, be prevented from spreading and danger of a wreck from this cause will be averted.

55 In order to prevent a rail from creeping

longitudinally there has been provided an anchor bar 7 which is also formed of steel or any other strong metal and has its end portions bent upwardly to form arms 8 and 9 which are bent to overhang the side portions 60 of the rail base, as shown in Figure 2. Referring to this figure, it will be seen that the distance between the inner edge faces of the upwardly extending portions of the arms is greater than the width of the rail base, and 65 therefore, the anchor may be readily applied to the rail by first engaging the arm 9 with one side portion of the rail base with the body of the anchor bar extending transversely beneath the rail and then swinging the anchor bar upwardly and sliding it in the reverse direction to dispose the inturned end portion of the arm 8 into overhanging engagement with the other side edge portion 70 of the rail base. The body portion of the anchor bar is of such length between the outer edge faces of the arms that the anchor bar may be snugly received in a slot 10 formed in the tie plate and, from an inspection of Figure 2, it will be readily seen that 75 when the anchor bar is seated in the slot formed in the tie plate and secured to the rail by the wedge 11, the rail will be very effectively held against longitudinal creeping. 80

After the anchor bar has been applied to the rail, the rail is seated upon the tie plate with the anchor bar fitted into the slot 10 and the spikes 5 at the side of the rail base engaged by the arm 8 may be driven through 90 the plate into the tie with their heads in firm gripping engagement with the rail base. After the spikes at this side of the rail have been driven into place, the wedge 11 is passed through the arm 9 with the adjacent side 95 edge portion of the rail base received in the longitudinal extending groove or recess 12 formed in the wedge. The wedge tapers towards one end, as shown in Figure 4, and it will be readily understood that when it is driven through the arm 9 it will serve to firmly hold the anchor bar in engagement with the rail and prevent danger of the rail creeping longitudinally through the anchor bar. After the wedge has been inserted the 100 remaining spikes are driven through the tie plate into the tie and the rail will be securely held in place. The anchor bar may, however, have limited vertical movement in the slot as the rail is moved downwardly by the 110

weight of a train and then returns to its normal position without this movement being transmitted to the rail plate and danger of the spikes being loosened by upward movement of the tie plate will be eliminated.

5 When the rail is to be removed and a new one substituted, it is merely necessary to withdraw the last mentioned spikes and drive out the wedge and the rail may be

10 lifted from the plate and the anchor bar disconnected from the old rail and applied to a new one which will, of course, be seated upon the tie plate and the withdrawn spikes and wedge replaced.

15 Having thus described the invention, I claim:

1. A tie plate having a slot formed therein and adapted to be secured upon a tie in position to extend beneath a rail, a rail anchor 20 adapted to engage the base of a rail with a portion extending beneath the base of the rail and fitted into the slot of said plate to hold the rail against creeping, and a wedge to hold said anchor in engagement with the 25 rail extending longitudinally of the rail when in place, said plate being formed with openings spaced from opposite sides of the slot and adapted to receive fasteners to secure the plate upon a tie, the fasteners when 30 in place positioned to engage the ends of the wedge and prevent withdrawal of the wedge.

2. A tie plate having a slot formed therein and adapted to be secured upon a tie in position to extend beneath a rail with the slot 35 disposed transversely thereof and projecting from opposite sides of its base, and an anchor bar adapted to fit into said slot transversely beneath a rail seated upon said plate and having portions extending upwardly 40 from the plate for engagement with opposite side portions of the rail base.

3. A tie plate having a slot formed therein and adapted to be secured upon a tie in position to extend beneath a rail with the 45 slot disposed transversely thereof and projecting from opposite sides of its base, an anchor bar adapted to fit into said slot transversely beneath a rail seated upon said plate and having portions extending upwardly 50 from the plate and shaped to over-

hang opposite side portions of the rail base, and a wedge for fitting between one upwardly extending portion of said anchor bar and a side portion of the rail base to firmly 55 secure the anchor bar in engagement with the rail.

4. A tie plate adapted to rest upon a tie beneath a rail and formed with a seat extending transversely beneath the rail, said plate being formed with openings spaced 60 from opposite sides of the seat and adapted to receive fasteners for engaging opposite sides of a rail base, an anchor removably fitted into said seat and having portions extending upwardly for overlying engagement 65 with opposite sides of a rail base, and a wedge for fitting between the rail base and one upwardly extending portion of said anchor to firmly hold the anchor in engagement 70 with the rail base, said wedge being held in place by fasteners passed through adjacent openings in said plate.

5. A tie plate adapted to rest upon a tie beneath a rail, a rail anchor adapted to engage 75 opposite side portions of a rail base and engaged with said plate to prevent movement of the anchor transversely and longitudinally of a track, a wedge to hold said anchor in engagement with a rail, and common means for securing said plate upon a tie and retaining the wedge in place.

6. A tie plate having a slot formed therein and adapted to be secured upon a tie in position to extend beneath a rail with the slot disposed transversely thereof and projecting from opposite sides of its base, and an anchor bar adapted to fit into said slot transversely beneath a rail seated upon said plate and having portions extending upwardly 80 from the plate and shaped to overhang opposite side portions of the rail base, one of the upwardly extending portions being spaced from the adjacent side edge of the rail and a wedge to fit tightly between the 85 last mentioned upwardly extending portion of said anchor bar and adjacent edge portion of the rail base.

In testimony whereof I affix my signature.

CARLTON T. MATTHEWS. [L.S.]
